ABSTRACT: An amplifier circuit including a Gunn effect semiconductor which exhibits increased limit frequencies and higher negative conductance. The Gunn effect semiconductor is constructed to possess a region in the vicinity of its cathode in which the field strength as effected by a steady state biasing voltage lies between the critical value at which the Gunn oscillation is initiated and a lower value at which the Gunn oscillation is extinguished, while the remainder of the semiconductor body possesses a field strength less than such lower value. The first region is periodically pulse triggered to initiate the Gunn oscillation, the period between pulses being approximately equal to the transit time of a high field zone through the semiconductor body. The triggering pulses may be produced by a second Gunn element or they may be produced in the first Gunn element itself.

SEMICONDUCTOR AMPLIFIER

BACKGROUND OF THE INVENTION

The article in the IEEE Transactions on Electric Devices, Volume ED-13, No. 1, page 110 and entitled "Microwave Amplification in a GaAs Semiconductor" by H. W. Thim and M. R. Barber discloses that it is possible to produce an amplification in a Gunn element having a subcritical n_0L product.

SUMMARY OF THE INVENTION

It is an object of the present invention to provide an improved semiconductor amplifier in which the limit frequency for the negative conductance as well as the useful negative conductance are increased and in which the amplifier arrangement may be of a particularly simple construction.

According to the present invention, the semiconductor body is subcritically biased in such a way that the effective field strength in the semiconductor falls between the critical value which determines the initiation of the high field zone producing the oscillation and the lower value which determines its extinction, the initiation of the high field zone being accomplished by a triggering pulse train whose periodicity approximately corresponds to the transit time of the high field zone through the semiconductor body.

BRIEF DESCRIPTION OF THE DRAWINGS

FIG. 1 is an amplifier circuit according to one embodiment of the invention.

FIG. 2 is an amplifier circuit according to a second embodiment of the invention.

FIG. 3 is a sectional view taken through a semiconductor constructed according to the present invention and illustrating one embodiment thereof.

FIG. 4 is a view similar to FIG. 3 but showing a modified form of construction.

FIG. 5 is a view similar to FIGS. 3 and 4 but showing a further modification of the semiconductor construction.

FIG. 6 is a graph illustrating the static and dynamic characteristics of the semiconductor device.

DESCRIPTION OF THE PREFERRED EMBODIMENTS

With reference to FIG. 1, the Gunn effect semiconductor which is responsible for the amplification is indicated by the reference character Pr_V and a second Gunn effect semiconductor used to trigger the amplifying semiconductor is indicated by the reference character Pr_0 . Both of these semiconductors may be connected to a common source U_B of biasing voltage, such source being bridged by the capacitor C_1 . The triggering semiconductor Pr_0 is in series, across the biasing source, with a circuit consisting of the resistor R_1 and inductance L_1 . The resistor R_1 serves as the DC load and the inductance L_1 as a choke for RF frequencies. The semiconductor Pr_V is in series, across the biasing source, with a circuit consisting of a DC load resistor R_2 and a choke inductance L_2 . The semiconductor Pr_V is coupled to the source G of the signal to be amplified, and whose frequency is indicated as f_s , by means of the resonant circuit consisting of the inductance L_3 and capacitor C_2 which are tuned to the signal frequency as indicated. The coupling is effected by means of a circulator Z_1 and the load resistance R_L is connected as shown. The two Gunn elements are connected by the resonant circuit tuned to the Gunn frequency, such circuit consisting of the inductance L_3 and capacitor C_3 as shown.

The Gunn element Pr_0 serves as an oscillator for the triggering pulses which, by virtue of the resonant circuit L_3 , C_3 coupling the two Gunn elements, so that high field zones are initiated in the semiconductor Pr_V . The periodicity of the triggering pulses approximately corresponds to the transit time of the high field zone through the body of the semiconductor Pr_V and, as discussed above, the semiconductor Pr_V is biased by the source U_B subcritically such that the effective field

strength in the semiconductor Pr_V falls between the critical value which determines the initiation of the high field zone and the lower value which determines its extinction.

The circuit according to FIG. 2, illustrates the manner in which the triggering pulses are effected in the amplifying semiconductor so that the DC current requirement for the circuit is reduced. As shown, the amplifying Gunn element Pr_V receives its bias from the operating voltage source U_B bridged by the capacitor C_1 and, as before, the semiconductor is subcritically biased thereby. The capacitor C_3 and inductance L_3 comprise a resonant circuit tuned to the Gunn frequency f_G which is connected to a further parallel circuit tuned to the signal frequency f_s and which consists of the inductance L_6 and capacitance C_6 so that the Gunn element, the bias source and the parallel resonant circuits are connected in series as shown. The signal to be amplified is fed into the circuit again through a circulator Z_1 , a series resonant circuit consisting of capacitance C_2 and inductance L_4 being connected therebetween. This series resonance circuit is connected at its one end with one arm of the circulator Z_1 and at its other end leads to the parallel resonant circuit tuned to the Gunn frequency.

Due to the load resistance being capable of resonance the field within the semiconductor body is controlled during each period of the alternating voltage to exceed the critical field strength E_K required to initiate the Gunn oscillations. This is possible in that the Gunn element is disposed on a resonator tuned to the Gunn frequency, the resonator being of such quality that the positive half waves of the generated Gunn oscillations push the semiconductor body into the supercritical field range during each such positive half wave.

In a particularly advantageous embodiment of the present invention the required self-triggering is accomplished by a special configuration of the semiconductor body, i.e. there is a field strength within the semiconducting body near the cathode contact K as shown in FIG. 3 for example which effects the initiation of a Gunn oscillation, whereas in the remaining portions of the semiconductor body the field strength remains between the critical value E_K required to initiate the Gunn oscillations and the value E'_K required to extinguish the high field zones. These relations, of course, are due to the steady state biasing source.

FIG. 6 illustrates the field strengths as described. The drift velocity V is plotted against field strength E . The ascending curve branch reaches the critical value at point E_K whereas a high field zone is initiated within the semiconductor body and, as indicated, this field strength is approximately 3.6 kv./cm. and the ascending curve branch represents the static characteristic of the semiconductor. The other curve branch represents the dynamic characteristic and, in particular, the useful negative conductance. At the field strength marked E'_K , the high field zones are extinguished and, as indicated, this value is approximately at 2 kv./cm. The product n_0L of electron equilibrium concentration times length of the semiconductor body is $\geq 10^{12} \text{ cm.}^{-2}$. The above-mentioned self-triggering can now be realized in the following manner. The semiconductor body can be doped in the vicinity of the cathode contact K in such a manner that this area receives less doping than the remaining area of semiconducting body Pr_V toward anode contact A . FIG. 3 is a schematic illustration thereof. It is also possible to produce the required field strength on the cathode side of semiconductor body Pr_V to initiate triggering in that the semiconductor body is provided with the same doping over its entire length and the cathode contact K is selected to be smaller than the cross section of the subsequent portion of the semiconductor body. The anode contact marked A extends, as is shown in FIG. 4, over the entire width of the semiconductor body. The probably most advisable embodiment, however, is that where, according to FIG. 5, the cross section of the semiconductor body is reduced on the side facing the cathode connection K over a relatively short length with respect to the remaining cross section. In FIG. 5, a_1 indicates the reduced cross section on the cathode side, whereas

the normal cross section of the semiconductor body P_r is marked a_2 . The anode connection is marked A. With the same specific resistance of the semiconductor material in both sections having different cross sections

E'_K/E_K must be smaller than $a_1/a_2 < 1$

so that the necessary high initiation field strength $E > E_K$ appears at the cathode and the desired low drift field strength E_D in the main portion of the semiconductor body, where $E'_K < E_D < E_K$. In order to prevent double initiation of the high field zones, the following condition should preferably be met

$$I_D/I_K < a_1/a_2$$

where I_D is the current density in the travelling high field zone and I_K the current density at the critical field strength. Deviating from the embodiment shown in FIG. 5 in which the transition from the small to the normal cross section of the semiconductor body occurs suddenly, it is also possible to provide this transition in several stages or continuously.

An amplifier constructed according to the present invention can also be so constructed that the Gunn oscillation which effects the negative conductance is utilized for the frequency conversion of the signal oscillation. Depending on whether the frequency conversion which preferably utilizes the semiconductor body itself as its nonlinear element, effects an upward or downward mixing, the mixer arrangement may be constructed either with preamplification or subsequent amplification.

An amplifier constructed according to the present invention produces, after biasing, an increase in the negative conductance which amounts to five to 20 times its value. Moreover, the limit frequency of the triggered amplifier is increased by approximately twice its value.

It will be understood that the above description of the present invention is susceptible to various modifications, changes and adaptations.

We claim:

1. An amplifier in which the negative differential conductance produced during the passage of a high field zone through a Gunn effect semiconductor is utilized for amplification, said amplifier comprising in combination;

a Gunn effect semiconductor;

means for biasing said semiconductor such that the effective field strength within said semiconductor lies between its critical value which determines the initiation of a high field zone and a lower value which extinguishes a high field zone; and

means having a pulse train output for periodically triggering said semiconductor above its critical value, the periodicity of which pulse train output is approximately equal to the transit time of a high field zone through said semiconductor.

2. The amplifier according to claim 1 wherein the last-mentioned means comprises a second Gunn effect semiconductor.

3. The amplifier as defined in claim 2 including a separate load circuit for each semiconductor;

a circuit connecting said semiconductors and tuned to their Gunn frequencies;

an oscillating signal source which is to be amplified; and said signal source being connected to the first-mentioned semiconductor through a circulator and a circuit tuned to the signal frequency.

4. The amplifier according to claim 1 wherein the last-mentioned means includes said semiconductor.

5. The amplifier according to claim 4 wherein said last means also includes a resonator tuned to the Gunn frequency

and connected to said semiconductor so that the positive pulses of the Gunn oscillations extend said semiconductor above its critical value.

6. The amplifier according to claim 5 including an oscillating signal source;

a first circuit tuned to the Gunn frequency and a second circuit tuned to said signal frequency, said first and second circuits being connected to said semiconductor; and means for selectively connecting said signal source to said first and second circuits.

7. The amplifier according to claim 4 wherein said semiconductor is of reduced cross section in the vicinity of its cathode whereby said means for biasing produces a field strength in the vicinity of said cathode which is above said critical value while the field strength in the remaining portion of said semiconductor lies between said critical and lower values; with:

$$I_D/I_K < a_1/a_2$$

where

a_1 = cross-sectional area in the vicinity of said cathode

a_2 = normal cross-sectional area of said semiconductor

I_D = current density in the traveling high field zone

I_K = current density at the critical field strength.

8. The amplifier according to claim 7 wherein said semiconductor is of reduced doping in the vicinity of said cathode.

9. The amplifier according to claim 7 wherein said cathode contacts said semiconductor over an area smaller than the cross-sectional area of the semiconductor in the vicinity of said cathode.

10. The amplifier according to claim 7 wherein said semiconductor is of reduced cross-sectional area in the vicinity of said cathode.

11. Amplifier as defined in claim 10 wherein the transition from the smaller to the normal cross section of the semiconductor body occurs in one jump.

12. The amplifier according to claim 1 including an oscillating signal source, said semiconductor being connected thereto for frequency conversion of said oscillating signal.

13. In a circuit for amplifying an oscillatory signal, the combination comprising;

a Gunn effect semiconductor having a body provided with an anode at one end and a cathode at its other end, and including means for producing regions having field strengths of different values in said body between said anode and said cathode in response to a predetermined steady state biasing voltage applied across said anode and said cathode, the region having a field strength of higher value being in the vicinity of said cathode and its field strength as effected by said predetermined steady state biasing voltage lying between the critical value of said semiconductor required to initiate the Gunn oscillation and that lower value required to extinguish the Gunn oscillation, the other region having a field strength as effected by said steady state biasing voltage which is less than said lower value required to extinguish the Gunn oscillation;

means for applying said predetermined steady state biasing voltage to said semiconductor body; and

means for periodically increasing the field strength in said region in the vicinity of said cathode to a value higher than said critical value whereby to initiate the Gunn oscillation, the periodicity of such periodic increase being approximately equal to the transit time of a high field zone through said semiconductor body.
